UNITED STATES PATENT OFFICE.

HOBERT A. STACY AND GEORGE A. OLSEN, OF CHICAGO, ILLINOIS, ASSIGNORS TO
SUCCESS CALENDAR STAND COMPANY, A FIRM CONSISTING OF LOUISE F. STACY,
GEORGE A. OLSEN, AND HOBERT A. STACY, ALL OF CHICAGO, ILLINOIS.

CALENDAR STAND OR SUPPORT.

Application filed December 18, 1922. Serial No. 607,504.

To all whom it may concern:

Be it known that we, HOBERT A. STACY and GEORGE A. OLSEN, citizens of the United States, and residents of the city of Chicago, 5 in the county of Cook and State of Illinois, have invented certain new and useful Improvements in a Calendar Stand or Support; and we do hereby declare that the following is a full, clear, and exact description 10 of the same, reference being had to the accompanying drawings, and to the numerals of reference marked thereon, which form a part of this specification.

This invention relates to a calendar stand 15 or support of that type commonly used on desks, and upon which a pack of leaves or sheets with dates imprinted thereon are adapted to be retained in book form whereby a leaf may be daily turned and data record- 20 ed thereon.

In the past, various calendar stands have been used in which a U-shaped hinge member retained the calendar leaves. These U-shaped members were variously attached, 25 sometimes by nuts and sometimes by latching means on the back of the stand, and in renewing the pack of calendar leaves, it was a tedious and laborious task to assemble and 30 disassemble the parts.

According to this invention, the U-shaped 35 loop that forms the hinge member for the leaves is so connected to the base that it may be readily moved to its operative or inoperative position for disassembling or assembling a pack of calendar leaves, and resilient 40 means are provided that automatically cooperate with the hinge member for yieldingly retaining the same in its different positions.

This invention comprises the novel structures and combinations hereinafter described and more particularly pointed out and defined in the appended claim.

In the accompanying drawings, which illustrate a preferred embodiment of this invention, and in which similar reference numerals refer to similar features in the different views:

Figure 1 is a sectional view through the stand, showing parts in elevation.

Figure 2 is a top plan view of the stand.

Figure 3 is an end elevation of the stand in use upon a reduced scale.

In referring now to the drawings, it will be observed that the stand comprises a platform 1 provided with a supporting leg or rest 2. In the present instance the platform is illustrated as converging upwardly from a substantially center transverse line 3, the leg 2 being positioned beyond the center line 55 upon what may be termed the upper part of the stand and its foot being beveled or inclined in a longitudinal direction with respect to the stand so that the stand may be supported upon the lower edge 4 of the platform 1 and upon the inclined foot, assuming 60 an inclined position with respect to the longitudinal axis of the stand.

The hinge or arched filing member for retaining the calendar leaves upon the stand 70 comprises a wire rod having a transverse hinge portion 5 and a pair of spaced upwardly extending U-shaped portions 6 integral with the base portion 5. The hinge portion 5 is rotatably secured upon the upper portion of the base by staples or eyes 7. The medial portion of said transverse hinge portion 5 is provided with a downward and rearwardly extending offset 8 which extends through an aperture 9 in the platform. 75 and a resilient means in the form of a leaf spring 10 bears against the inclined offset 8 for normally holding the hinge member in its operative position as shown. The ends of the U-shaped portion 6 are adapted to 80 normally rest in slight depressions 11 formed in the lower portion of the platform.

From the foregoing, it is apparent that the hinge member for the calendar leaves may be readily swung upwardly or rearwardly upon the transverse portion 5 as an axis. During such movement, the inclined offset 8 will move in an arc and as it passes the point of dead center, the spring 10 will assist in snapping the hinge member rearwardly. In its inoperative position, the offset 8 will be inclined in the opposite direction to that shown so that the thrust of the spring will yieldingly hold the hinge member in its inoperative position, as is obvious. 95

It will be apparent from the simple operation of the hinge member, that a pack of

2
leaves may readily be assembled or disassembled with respect thereto, avoiding the inconvenience and labor arising from using the old forms.

5 We are aware that numerous details of construction may be varied through a wide range without departing from the principles of this invention, and we therefore do not purpose limiting the patent granted otherwise than necessitated by the prior art.

We claim as our invention:

In a calendar stand, a hinge member for the leaves, pivotally secured to the upper face of the stand and swingable in an arc

from operative to inoperative position, and 15 a yielding member secured to the lower face of said stand and co-operating with said hinge member for yieldingly retaining the same in either of its positions.

In testimony whereof, we have hereunto 20 subscribed our names in the presence of two subscribing witnesses.

HOBERT A. STACY.
GEORGE A. OLSEN.
